ANTENNA

Andrew Alford, Cambridge, Mass.

Application January 13, 1949, Serial No. 70,752

15 Claims. (Cl. 250—33)

1

This invention relates to antennas for ultrahigh frequencies and more particularly to antennas for broadcasting ultrahigh frequency horizontally polarized waves.

This invention makes use of a number of small loops shunted across a balanced transmission line arranged so that a large number of loops may be cophasally energized thereby obtaining a large concentration or radiant power in a plane in which the radiation is distributed in a substantially circular pattern.

One object of this invention is a simple antenna with low windage that could be installed on tall metal masts and energized with one feeder.

Another object of my invention is an antenna that has power gain with respect to antennas of prior art so that two antennas of the invention could be used to produce the same concentration of radiated field as is normally produced by four antennas of the prior art. This result is particularly desirable where a large power gain is desired without employing the customary stacked array consisting of a number of antennas requiring individual means for phasing with the necessary fittings, and transformers must be provided.

Still another object of my invention is an antenna which radiates horizontally polarized waves substantially equally in all horizontal directions when installed on a metal pole.

A further object of my invention is an antenna which is so arranged that it may be conveniently fed by a coaxial transmission line having a characteristic impedance of the order of 70 ohms.

These and other objects of this invention will more clearly appear from the appended claims and the description which with the aid of Fig. 1 explains certain phases of the invention. Fig. 2 is a graph showing certain factors affecting the operation of the antenna of the invention, and Figs. 3 and 4 show two embodiments.

1 and 2 in Fig. 1 are conductors of a balanced transmission line that is shunted by a plurality of conductors bent into loops such as 3, 4, 5. At one end the conductors 1, 2 are connected to a balanced ultrahigh frequency power source 6. The opposite end of the transmission line is short-circuited by a bar 7. When the number of loops 3, 4, 5, etc. per free space wavelength measured along conductors 1, 2 is of the order of 10 and the diameter of each loop is of the order of .115 wavelength, then the loops 3, 4, 5, etc. will substantially increase the phase velocity at which waves are propagated along conductors 1, 2.

2

The waves propagated along conductors 1, 2 are reflected from short-circuiting bar 7, whereby standing waves are produced along conductors 1, 2. The difference of potentials between conductors 1, 2 is distributed as indicated by curve 8 in Fig. 1. The difference of potential is substantially zero at the short-circuiting bar 7, reaches a first maximum at 9, the first minimum at 10 and a second maximum at 11. The distance between the first minimum 10 and the short-circuiting bar 7 is substantially equal to half of the free space wavelength at the frequency of source 6 when all the loops are removed. When the loops are shunted across the transmission line 1, 2 the distance between 9 and 7 is greater than a free space half wavelength by a factor K which is a function of the diameter D of each loop and of the spacing L between the consecutive loops.

Fig. 2 shows how the value of K is affected when the diameter D is varied while the ratio L/D is kept constant. In Fig. 2 the diameter D in free space wavelength is plotted along the abscissa and the value of K is the ordinate. Curve 14 indicates the values of K which corresponds to different values of D when the value of L/D is 1.79. Curve 15 shows the value of K which corresponds to different values of D when L/D=.895. Curve 16 shows the value of K for different values of D when the loops have been replaced by a continuous cylindrical sheet of the same diameter. This case corresponds to a very large number of loops adjacent to and in contact with each other, so that the spacing L between them is substantially zero and L/D=0.

It may be seen from Fig. 2 that when the diameter D of each ring is .11 wavelength and the spacing L between the consecutive loops is such that L/D=.895 the distance between the first minimum 10 and the short-circuited bar 7 is approximately two free space half wavelengths. It is found that under these conditions the potentials applied to all loops that are connected to conductors 1, 2 between 7 and 10 in Fig. 1 are substantially in the same relative phase except in the immediate vicinity of the minimum 10.

The principles explained in connection with Figs. 1 and 2 are utilized in the construction of the antenna of Fig. 3. In the figure, conductors 21, 22 and loops 23, 24, 25 correspond to conductors 1, 2 and loops 3, 4, 5 in Fig. 1. Movable short-circuiting bar 26 is used to reflect waves originated by ultrahigh frequency source 27 which supplies ultrahigh frequency power through coaxial transmission line 28 to conductors 21, 22. The inner conductor 29 of the

coaxial transmission line 28 is connected to conductor 22. The outer conductor of line 28 is connected to conductor 21. Movable short-circuiting bar 31 connected across the coaxial transmission line and a tube 30 attached to the lower end of conductor 22, provides a means for improving the impedance match between the balanced transmission line 21, 22 and the coaxial transmission line 28 while at the same time insuring nearly equal and opposite voltages along conductors 21, 22.

Curve 32 indicates the distribution of the difference of potential existing between conductors 21, 22. At a point 33 the difference of potential is maximum. With the aid of such data as is shown in Fig. 2 the distance between 26 and 31 may be selected so that 33 is located approximately halfway between the short-circuiting bars 26 and 31. The final adjustments may be made by moving short-circuiting bar 26 toward or away from 31. When short-circuiting bar 26 is in such a position that the first minimum is at or near 31, the impedance presented to the coaxial transmission line 28 will be nearly a pure resistance. The value of this resistance depends on the distance between ends 34 of the coaxial transmission line sections 28a, 30 and short-circuiting bar 31. By moving 31 toward 34 and then by correspondingly adjusting the position of 26 the value of the impedance presented at the end of the coaxial transmission line 28 may be reduced. By moving 31 away from 34 and by correspondingly adjusting 26, the value of impedance presented to line 28 may be increased. Such adjustments may be used to achieve either a good match between line 28 and the balanced line 21, 22 or to provide a convenient value of impedance for matching the concentric line 28 with known means such as a quarter-wave transformer.

The phase of the difference of potential between conductors 21, 22 is substantially constant at the points where loops 23, 24, 25, etc. are connected. The currents which flow in the loops are therefore substantially in the same relative phase with each other so that the loops are effectively arranged in a stacked cophasal array. This fact results in a substantial concentration of the power radiated by the loops in the direction of the plane passing through the halfway point along conductors 21, 22 and at right angles to the long dimension of said conductors 21, 22. The greater is the total distance or span between the end loops 35, 36, the greater is the concentration of energy in the direction of said plane at right angles to the conductors 21, 22. Since the total span between the end loops that can be cophasally energized may be increased only when the distance between 26 and the first minimum is increased, it is desirable to select those combinations of loop diameter D and loop spacing L which result in a large value of K. This may be done with the aid of such curves as are shown in Fig. 2. Thus, for example, by selecting loop diameter of .11 wavelength and by spacing these loops so that $L/D = .895$ it is possible to feed cophasally with one feeder a stack of loops having a total span approximately .8 wavelength.

The loops 23, 24, 25, etc. may be conveniently supported by a metal pole 37 at neutral points such as 38a along loop 23. Neutral point 38 is equidistant from conductors 21, 22 as measured along conductors of loop 23. Since the potential at a neutral point such as 38a is substantially zero, no distortion of radiation pattern occurs when the neutral points of each loop are

bolted directly to a metal mast 37 or to an auxiliary metal channel 38 which is bolted 38b to the pole. Furthermore, since the potential increases gradually from zero on both sides of a neutral point, a clamp of adequate size may be used without substantially affecting the operation of the antenna. Additional bracing may be provided by extending conductors 21, 22 to metal pole 37 where said conductors may be clamped to the pole at points such as 39, 39a.

A still greater concentration of radiant power may be obtained with the arrangement of Fig. 4 which shows another embodiment of my invention. In this figure, 40 is a source of ultrahigh frequency power used to supply conductors 41, 42 through coaxial transmission line 43 and an auxiliary balanced feeder 44, 45. Loops such as 46, 47, 48, etc. are shunted across conductors 41, 42 on both sides of the auxiliary feeder 44, 45. Movable short-circuiting bars 49, 50 are shunted across conductors 41, 42 near their ends.

The reflection of waves at short-circuiting bars 49, 50 results in a difference of potential between conductors 41, 42 which is distributed as shown by curve 51. Some of the loops, e. g. 46, are between short-circuiting bar 49 and the first potential minimum 52, and others, such as 47, 48, are shunted across conductors 41, 42 between short-circuiting bar 50 and the potential minimum 53. Preferably no loops are provided between minima 52, 53. This arrangement provides, therefore, two sets of loops, the loops in each set being energized in the same relative phase with each other.

When the minima 52, 53 are at substantially equal distances from the auxiliary feeder 44, 45, the loops in the upper and lower sets will be energized in the same phase.

The loops in the two sets will be energized in the same phase when the distances between short-circuiting bars 49, 50 and feeder 44, 45 are less than the distance from 49, 50 to the nearest minima 52, 53 so that these minima do not appear along conductors 41, 42 but along feeders 44, 45. The distance between 49 and feeder 44, 45 is preferably made equal to the distance between 50 and 44, 45. Furthermore, both these distances are preferably so chosen that there is a minimum in the neighborhood of end 54 of concentric transmission line 43. This proportioning allows a better match between coaxial transmission line 43 and the transmission line 41, 42. A movable short-circuiting bar 55 across 44, 45 provides an additional means for making impedance adjustments while performing its main function of insuring substantially equal and opposite voltages on feeders 44, 45 and, therefore, also on conductors 41, 42.

The loops may be clamped directly to the metal pole 56 or to an auxiliary metal channel 57 bolted to the pole at neutral points such as 57a. The ends of conductors 41, 42, may be extended beyond the movable short-circuiting bars 49, 50 and clamped to the metal pole 56 at 58, 59 to provide for additional bracing of the structure.

The current flowing in a loop is maximum at the neutral point but gradually decreases toward the ends of the loop. The minimum value of current is at the points where the loop is connected to conductors 41, 42. The radiation pattern of such a loop in the plane of the loop is therefore not quite an exact circle but an oval with maxima along the diameter which passes through the neutral point 57, and the minima in directions approximately at right angles to said diameter.

As the size of the loop is decreased the radiation pattern approaches a perfect circle.

The radiation resistance of each loop varies with the loop diameter. This radiation resistance of a loop consists of two parts; the radiation resistance proper and the mutual radiation resistance. For two closely spaced loops the mutual radiation resistance is approximately equal to the radiation resistance proper so that each loop has a total radiation resistance equal to about twice the radiation resistance it would have if it were alone. For a number of closely spaced loops the total radiation resistance of each loop is several times as great. When loops are decreased in size and are at the same time separated by greater spaces the radiation resistance of each loop decreases very rapidly until it becomes comparable with the high frequency resistance of the loop conductors. When these two resistances become comparable substantial portion of the power is lost in heating loop conductors. This undesirable condition is usually reached with loops smaller than .07 wavelength in diameter. There are therefore both lower and upper practical limits of the size of loops that may be efficiently used in antennas of Figs. 3 and 4.

Furthermore, as may be seen from Fig. 2, loops having diameters greater than .17 of a wavelength must be closely spaced requiring a large number of loops per unit length in order that a span of cophasally energized loops may be greater than .7 of free space wavelength. Loops, whose diameters are less than .07 λ , are inefficient and require high currents. The optimum size of loops is between these two limits in the neighborhood of .115 wavelength.

This optimum loop size is affected to some degree by certain other factors and more particularly by the shape of the cross section of the loop conductors and by the characteristic impedance of the transmission line 41, 42 between the loops.

As the cross section of the individual loop conductor is reduced, the reactance of each loop is increased requiring a smaller spacing between loops. An increase in cross section of loop conductors has an opposite effect, requiring an increase in spacing between loops.

A decrease in the characteristic impedance of the transmission line 41, 42 requires a proportional decrease in reactance of individual loops or a closer spacing between them. With loops of the order of .115 wavelength in diameter spacing of the order of .10 wavelength is convenient. With loops of smaller diameter smaller spacing may be desirable in order to avoid substantial portion of the power being radiated by the transmission line in the form of vertically polarized radiation which under ordinary circumstances is essentially lost so far as useful effects are concerned.

Curves 14, 15, 16 in Fig. 2 are given for typical proportions of loops and of transmission line conductors. These curves are based on data obtained with loops made of metal bands of the order of $\frac{1}{80}$ of a free space wavelength wide and about $\frac{1}{1000}$ of a wavelength thick. The transmission line conductors were made of metal strips $\frac{1}{80}$ wavelength wide and about $\frac{1}{500}$ wavelength thick and spaced about $\frac{1}{50}$ wavelength between the nearest edges.

When the loops are not formed into circles but into other shapes, e. g. an ellipse, a rectangle, etc.—all shapes being covered by the word “loop” as used in this specification—the operation of the antennas of Figs. 3 and 4 is substantially the

same as above described provided that the loops have about the same area as circular loops whose diameters are between .07 and .17 wavelength, i. e. an area between .00384 and .0227 square free space wavelengths.

The spacing of the transmission line 21, 22 in Fig. 3 and 41, 42 in Fig. 4 is not critical, but should be of the order of a fraction of a wavelength.

It will be clear from the foregoing that broadcasting antennas of the present invention can be manufactured in a shop and then installed on a mast without requiring the soldering of many joints, and that the finished antenna will have low windage and the required qualities as a radiator.

This application contains the subject matter set forth in my previously filed application, Serial Number 644,519, filed January 31, 1946, now abandoned.

Having now described my invention, I claim:

1. In an antenna, a transmission line, a plurality of more than two loops shunted across said line and means for energizing said line with ultra-high frequency band of radio waves, said loops being spaced sufficiently close to one another and dimensioned for such a size whereby said loops are contained in a space not more than one-half of an apparent free wavelength of a transmitted wave in the band as adjusted by a value K greater than 1 corresponding to a phase correction of the actual free space wavelength due to an increased potential velocity established by the size and spacing of said loops, the area enclosed by said loops being between $.0227\lambda^2$ and $.00384\lambda^2$ where λ is said free space wavelength corresponding to said frequency within the transmission band.

2. The antenna according to claim 1, and in which all the loops are alike.

3. The antenna according to claim 1, and in which the loops have circular shapes with diameters between $.17\lambda$ and $.07\lambda$ corresponding to a transmitted frequency within the frequency operating band.

4. The antenna according to claim 1, and in which the loops have circular shapes with diameters substantially $.115\lambda$ where λ corresponds to a transmitted frequency within the frequency operating band.

5. The antenna according to claim 1, and in which the loops are cophasally energized.

6. The antenna according to claim 1 having a total span in which the loops are contained substantially $.8\lambda$ where λ corresponds to a wavelength of a transmitted frequency within the frequency operated band.

7. The antenna according to claim 1 in which the means for energizing the transmission line is connected thereto near one end thereof.

8. In an antenna, a balanced transmission line, a plurality of circular metal loops shunted across said line, each having a diameter substantially $.115\lambda$, λ corresponding to a frequency within the transmitted frequency band, the ratio of the space between adjacent loops measured in said wavelength to the said diameter being substantially .895, an unbalanced-to-balanced radio frequency transformer, a concentric transmission line connected to the balanced line near one end thereof through said transformer, the transformer including a movable short-circuiting bar for adjusting the impedance of the coaxial line to that of the balanced transmission line, a movable short-circuiting bar near the other end of the balanced transmission line, a metal mast,

75

means for attaching the midpoint of the loops to the mast and means for attaching said other end of the unbalanced transmission line to the mast.

9. In an antenna, a balanced transmission line, a plurality of circular metal loops shunted across said line, each having a diameter substantially $.115\lambda$, λ being a wavelength in the transmitted band, the ratio of the spacing between adjacent loops to said diameter being as small as .895, a 10 concentric transmission line, an unbalanced-to-balanced radio frequency transformer for connecting the last mentioned line to the balanced line near the middle point of the latter, movable short-circuiting bars near the ends of the balanced line, a movable short-circuiting bar operatively connected with said transformer for adjusting the impedance of one line to that of the other, a metal mast, means for attaching the midpoints of the loops to the mast, and means for attaching the ends of the balanced transmission line to the mast.

10. In an antenna, a transmission line, a plurality of more than two loops shunted across said line and means for energizing said line with ultra high frequency radio waves, said loops being spaced sufficiently close to one another and dimensioned for such a size whereby said loops are contained in space not more than one-half of an apparent free wave length of the transmitted wave as adjusted by a value K greater than 1 corresponding to a phase correction of the actual free space wave length due to the increased potential velocity established by the size and spacing of said loops, said spacings between loops divided by the loop diameter being substantially .895 and the diameter of said loops being not greater than $.17\lambda$ where λ corresponds to the transmitted frequency within the frequency operating band.

11. In an antenna, a transmission line, a plurality of more than two loops shunted across said line and means for energizing said line with ultra high frequency radio waves, said loops being spaced sufficiently close to one another and dimensioned for such a size whereby said loops are contained in space not more than one-half of an apparent free wave length of the transmitted wave as adjusted by a value K greater than 1 corresponding to a phase correction of the actual free space wave length due to the increased potential velocity established by the size and spacing of said loops, said antenna having a short circuit connector near one end of the transmission line.

12. In an antenna, a transmission line, a plurality of more than two loops shunted across said line and means for energizing said line with ultra high frequency radio waves, said loops being spaced sufficiently close to one another and dimensioned for such a size whereby said loops are contained in space not more than one-half of an apparent free wave length of the transmitted wave as adjusted by a value K greater than 1 corresponding to a phase correction of the actual free space wave length due to the increased potential velocity established by the size and spacing of said loops, said means for energizing the transmission line being connected to the line at its mid-point and said line having short circuit elements near both ends thereof.

13. In an antenna, a transmission line, a plurality of more than two loops shunted across said line and means for energizing said line with ultra high frequency radio waves, said loops being spaced sufficiently close to one another and dimensioned for such a size whereby said loops are contained in space not more than one-half of an apparent free wave length of the transmitted wave as adjusted by a value K greater than 1 corresponding to a phase correction of the actual free space wave length due to the increased potential velocity established by the size and spacing of said loops, said means for energizing the transmission line being connected thereto near one end and movable short circuiting bars connected near both ends of said line.

14. In an antenna, transmission line, a plurality of more than two loops shunted across said line and means for energizing said line with ultra high frequency radio waves, said loops being spaced sufficiently close to one another and dimensioned for such a size whereby said loops are contained in space not more than one-half of an apparent free wave length of the transmitted wave as adjusted by a value K greater than 1 corresponding to a phase correction of the actual free space wave length due to the increased potential velocity established by the size and spacing of said loops, said means for energizing the transmission line being connected thereto near one end and means comprising a coaxial transmission line and an unbalanced-to-balanced radio frequency transformer, the coaxial line being connected to the transmission line element near one of its ends by the transformer and a short circuiting bar connected across the transmission line near its other end.

15. In an antenna, a transmission line, a plurality of more than two loops shunted across said line and means for energizing said line with ultra high frequency radio waves, said loops being spaced sufficiently close to one another and dimensioned for such a size whereby said loops are contained in space not more than one-half of an apparent free wave length of the transmitted wave as adjusted by a value K greater than 1 corresponding to a phase correction of the actual free space wave length due to the increased potential velocity established by the size and spacing of said loops, a metal support to which the loops are attached at their neutral points and means for attaching at least one end of the transmission line to the metal support.
